UNITED STATES PATENT OFFICE.

JOHN T. PSARSKI, OF CLEVELAND, OHIO, ASSIGNOR TO THE PSARSKI DYEING MACHINE COMPANY, OF CLEVELAND, OHIO, A CORPORATION OF OHIO.

DYEING-MACHINE.

1,155,438.

Specification of Letters Patent.

Patented Oct. 5, 1915.

Application filed February 28, 1910. Serial No. 546,414.

To all whom it may concern:

Be it known that I, JOHN T. PSARSKI, a subject of the Czar of Russia, residing at Cleveland, in the county of Cuyahoga and 5 State of Ohio, have invented certain new and useful Improvements in Dyeing Machines, of which the following is a specification.

This invention relates broadly to dyeing 10 machines and relates particularly to an improvement over the construction set forth in my Patent No. 955,993, issued April 26, 1910, wherein a tank forming a chamber which receives the mass to be dyed is provided with 15 a perforated false bottom and a perforated centrally disposed distributing member for distributing the dye liquor together with a cover for such tank provided with discharge openings adjacent the periphery thereof and 20 adapted to cause an outward and upward circulation of the dye liquor whereby the mass is expanded out laterally against the side of the tank and upwardly against the underside of the cover so that channeling 25 around the mass and through the mass is prevented.

This invention relates to the same type of machine except that the false bottom is preferably in the shape of an annulus and is adjustable relative to the central distributing member so that different quantities of material may be dyed in the machine effectively and with ease, and to means for raising the bottom against the mass as it shrinks 35 in size and during the operation of the machine.

The invention also relates to a modification of this machine wherein the discharge openings are arranged not only in the cover 40 but also in the side of the tank adjacent to the periphery of the cover whereby the discharge is increased and yet the lower part of the tank below the discharge openings is left imperforated to allow for the shrinkage 45 of the mass.

Further invention resides in the arrangement of a sampling device which is freely accessible from the outside of the machine and which will receive a portion of the mass 50 to be dyed so that the operator may determine at all times during operation just what is taking place within the machine.

Still further invention resides in certain

details of construction hereinafter set forth in the following description, drawings and 55 claims.

Referring to the drawings, Figure 1 represents a plant or machine constructed according to my invention; Fig. 2 is a top plan of the machine with the cover removed; 60 Fig. 3 is a vertical section showing a modified form of discharge; Fig. 4 is a side elevation of the tank with a portion broken away showing the sample box; Fig. 5 is a perspective view of the sample box; Fig. 6 65 is a detail of one of the blocks and screws for forcing down the cover; and Fig. 7 is a detail of one of the clips in place in a portion of the upper ring of the tank.

In carrying out the invention any preferred form and construction of parts may be employed so long as they possess the necessary characteristics, but I have shown herein one construction which produces very effective work, and in such embodiment 1 75 represents the base of the tank, which is provided with an annular groove 2 and ears 3 on the periphery of the base for receiving clamping bolts to be described. Centrally the base 1 is provided with an opening 4 to 80 receive the inlet pipe 5 and with another opening 6 to receive an outlet pipe 7. The base is also provided with an opening 8 for receiving a steam pipe 9 which is connected to a steam distributing pipe 10 within the 85 base of the tank and extending on the inside.

The tank proper is composed of a bottom 11 preferably of wood and adapted to rest upon the upper surface of the base 1 and 90 to engage an annular recess 12 in the side 13 of the tank. The side wall of the tank is preferably made of wooden boards, and the ends of these boards extend beyond the bottom 11 and into the recess 2. The boards 95 forming the side wall are held in circular arrangement or in cylindrical form by suitable metal straps 14. A shoulder 15 is provided on the interior at the upper edge of the side wall and this forms an annular upward projection 16 which engages in a recess 16' of the upper ring 17 of the tank. This ring 17 is preferably of cast metal and is provided with ears 18 for receiving through bolts 19 which pass through the ears 100 105 3 of the base and hold the upper ring and

the base together against the upper and lower edges of the side wall. The upper ring 17 is provided at several points around the periphery with a slot 20 having an upwardly extending recess 21 at one end and communicating with an internal recess 22 within the ring and at the back end of each slot 20. These slots and recesses form openings and securing shoulders for the clips and cover blocks and screws to be described.

Resting upon the bottom of the tank and against the side wall and secured in place if desired are supporting blocks 23 which are adapted to support, when in normal position, the false bottom 24 which is provided with perforations 25. This false bottom is in the form of an annulus having a large opening 26 at the center and recesses 27 at the inner periphery for a purpose to be described. This false bottom has secured in it the ends of a cable 28 which pass up through the cover and may be connected to a load hook A of a suitable hoist whereby the false bottom may be raised independently of other parts.

Resting upon the bottom and secured thereto if desired are other blocks 29 which are near the inner periphery of the false bottom and are adapted to support a central distributing member 30 which is preferably of cylindrical form having a lower flange 31 which rests upon the blocks 29 and extends under the edge at the inner periphery of the false bottom 24. The side wall of this distributing member is perforated with perforations of substantially the size of the perforations 25 in the base and is further provided with outwardly extending lugs 32 which are adapted to pass through the recesses in the inner periphery of the false bottom 24 and to engage upon the underside of the same and support it in any position so that the machine may be varied in capacity by elevating the false bottom on any of the lugs 32. The upper part of the distributing member extends inward with sloping sides to a central imperforate boss 33 and these sloping sides are provided with perforations 34 which are smaller than the perforations in the side wall of the central distributing member. The boss 33 is provided with an opening 35 which receives the threaded shank 36 of a bolt 37 which is secured in place in the distributing member by a nut 38 upon the underside of the boss 33. The upper end of the bolt is provided with an eye 39 in which may be secured the hook of a hoist.

Resting upon the boss 33 is the cover 40 which is preferably solid and has a central cylindrical portion 41 which has an opening therein slightly less in diameter than the diameter of the boss 33, but made sufficiently large to admit of access by the hand to the edge of the boss so that in packing the tank

any material, which may have gotten up over the edge of the boss and which would remain between it and the cover, may be removed and pushed into the tank. The upper edge of the central cylindrical portion 41 is finished to receive a nut 42 which is threaded onto the bolt 37 and is provided with peripheral openings 43 for a spanner wrench. The cover 40 is still further provided near its periphery with a group of discharge openings 44 which permit the passage of the dye liquor from within the tank to a point above the cover. The nut 42 holds the cover down upon the mass and the mass when it is first packed, holds the false bottom down upon the flange 31, and in order to hold all of these parts within the tank suitable blocks and screws and clips are provided. Each of the blocks comprises a body portion 45 having a threaded opening 46 therein for receiving a bolt 47 which is adapted to engage the cover. The body portion 45 of the block is also provided with a flat projection 48 which is adapted to extend through any one of the slots 20, 90 and a lug 49 extending upwardly from the flat projection and for engaging that portion of the ring 17 in front of the internal recess 22. The block may be locked in position by registering the lug 49 with the recess 22, and the flat projection with the slot 20. The block is then pushed outward from the center, or in other words, the flat projection is pushed into the opening and the block is then given a slight movement circumferentially with respect to the ring so that the lug 49 engages in the segmental recess 22. The block is then secured to the ring and the bolt 47 may be screwed down to force the cover and the other parts into the tank. When they have been forced down properly the cover clips may be put in place in other openings in the inner periphery of the upper ring 17, and the body portion 50 of these clips is similar in all respects to the body portion of the blocks, but in place of the screw 47 there is a long shank which is adapted to extend down and engage the cover. The object of the clips and the blocks and screws is that when the parts have been pressed down sufficiently the clips may be put in place and the screws removed so that the threads of the screws and the threads of the blocks are not impaired by the action of any acids which may be present in the dye liquor.

The side wall 18 of this style of tank is provided with a discharge opening 14' at a point above the point which the cover 40 normally assumes, and in this opening is secured a discharge pipe 51 which extends down and engages a three-way valve 52 which receives in one of its connections the pipe 7 and receives in the third a pipe 53 connected to the inlet of a centrifugal pump 130

54. A connection 55 is provided in this inlet of the pump 54 for a purpose to be later described.

It will be seen from the above connections 5 that by the operation of the valve 52 the liquor may be drawn from the bottom or the upper part of the tank, the former operation being conducted through the pipe 7, and the latter through the pipe 51, it being 10 obvious, of course, that when one is operating the other is closed.

The pipe 5 which is the inlet pipe to the bottom of the tank, leads to a three-way valve 56 secured to the outlet pipe 57 of the 15 pump 54. Another pipe 58 leads from the three-way valve 56 to a point above the top of the tank, so that instead of delivering the dye liquor from the pump to the bottom of the tank, by manipulation of the valve 56, 20 the liquor may be delivered to the top of the tank.

The side wall 13 of the tank is provided preferably at a point opposite to the opening 14 with another opening 14°, and this receives a pipe 59 provided with a valve 60 and suitable elbow connections and discharge pipe 61, and this pipe 61 is adapted to deliver the liquor from above the cover to a heating tank 62 which is provided at 30 its bottom with a steam inlet pipe 63 and with a discharge pipe 64, which is connected to a valve 65. This valve 65 is connected by a short pipe 66 with the connection 55 at the inlet of the pump.

35 In operating the machine, normally the mass is placed above the false bottom and within the chamber formed by the side wall of the tank, so that it is arranged around the central distributing member. When the 40 proper amount of material has been placed within the tank the cover is put on and is forced down, and by means of the nut 42 the lower edge of the cylindrical portion 41 is brought down so that it engages the boss 45 33. If any material should rest upon the boss it may be removed by the hand through the opening within the cylindrical portion 41 before the nut 42 is brought down in place. The parts are then held within the 50 tank by means of the blocks and screws and finally by the clips before referred to, and dye liquor is supplied to the machine from the tank 62 where it is being heated by steam from the steam pipe 63, the liquor 55 being drawn from this tank through the center of the pump 54 and being then pumped up through the machine through the pipe 5. The dye liquor may be permitted to pass out through the pipe 59 and 60 through the course just described to the pump, the valve 52 being closed for both connections 57 and 51, but when it is desired to cut off the circulation through the tank 62 the valves 60 and 65 are closed and 65 the valve 52 is set so that the pump is draw-

ing the liquor through the pipe 51 from the top of the machine and delivering it through the pipe 5 to the bottom of the machine or the operator may set the valve so that the liquor may be drawn from the bottom of the 70 machine and delivered through the pipe 58 above the cover. In fact many times it happens that better results are produced by first directing the dye liquor upwardly from the bottom through the mass and then reversing the direction of the dye liquor by delivering it above the cover by the pipe 58 and sucking it through the mass to the pump. Any desired circulation of the dye liquor through the tank or to the heating 80 tank 62 may be brought about.

In the modification of the invention shown in Fig. 3, the side wall 67 is provided with an annular group of perforations 68 which extend above and below the periphery of the 85 cover when it is in normal position and the outside of the tank is provided with an annular casing 69 which is secured to the side of the tank. This annular casing has a suitable connection for the discharge pipe 90 51. In this embodiment the discharge openings are at the juncture of the cover and the side wall and are below and above the periphery of the cover.

In order that the operator may know the 95 condition of the material within the tank a test box is provided for use in conjunction with the discharge of the tank, and this test box comprises a heavy base 100 which is in the form of a frame having an opening 71 therein and a framework 72 which receives on all sides wire net 73. A cover 74 is hinged to this framework and is provided with a suitable latch 75 which engages a pin 76. This box is either secured or set upon the cover adjacent to the discharge opening for the pipe 51 so that the dye liquor from the tank is drawn up through the opening 71 in the base of the box, through the wire net which is on all 105 sides and through the sample of the material which is placed within the box, so that by reason of the looseness of this sample and by reason of its small size the dye is distributed through it and it is in the same condition which prevails in the material within the tank so that the operator by observing this sample may know exactly 110 what is taking place within the machine.

If it should be desirable at any time to 120 reduce the capacity of the machine, this may be accomplished, before the tank is filled, by shifting the bottom so that the recesses at the inner periphery are in vertical alinement with the lugs on the exterior 125 of the central distributing member when the false bottom may be raised or lowered past any of the lugs and then rotated so that when it is released again it will rest on other lugs whereby when the machine is 130

packed, it will receive less or more material as the case may be. The object of raising the false bottom to decrease the capacity of the machine is that no matter what the 5 amount of the mass to be dyed may be, it will be held up against the underside of the cover upon the initial starting of the machine, for it is quite obvious that if there were a small mass of material in the bottom 10 of the chamber, the dye liquor could flow over the mass from the center to the periphery and satisfy the force of the circulation, thereby forming a channel, and if this channel is formed there is nothing to circulate 15 the dye liquor through the mass.

By the arrangement of the cable connections with the false bottom the latter may be moved upward against the material as it shrinks during the dyeing operation, and 20 if desirable the lugs about the central distributing member may be eliminated and the change in the capacity of the machine may be brought about by varying the position of the false bottom prior to the dyeing operation or after the material has become 25 moistened with the liquor, as the false bottom may be raised until the material is forced against the underside of the cover by it. In this way the parts may be arranged so that the dyeing machine is of any 30 capacity and any quantity of material may be dyed in it.

Having described my invention, I claim:

1. In a dyeing machine, a receptacle forming a chamber for receiving the material to be dyed and having a wall against which the material is to be compacted, top and bottom members for said receptacle, said wall being provided with a group of discharge 35 openings adjacent one of said top and bottom members only, and means for supplying the dye liquor to the mass at a point on the opposite side thereof from the discharge. 40

2. In a dyeing machine, a receptacle forming a chamber having a vertical wall provided with an imperforate part and a group of perforations extending around the entire tank, said wall being adapted to have the material compacted against the same, top 45 and bottom members, one of which is arranged adjacent the imperforate part of the wall and the other is adjacent the perforated part, such member adjacent the perforated 50 part being provided with discharge openings adjacent the discharge openings in the wall, and means for supplying the dye liquor to the mass at a point opposite to the discharge whereby the mass is forced against the imperforate part of the wall and against the 55 member having the discharge openings. 60

3. In a dyeing machine, a tank adapted to receive the material to be dyed and having on its side an imperforate portion and a 65 group of discharge openings, top and bottom members, one arranged adjacent the im-

perforate portion and the other arranged adjacent to the discharge openings, said last named member having discharge openings adjacent the discharge openings in the side of the tank, and means for delivering the 70 dye liquor to the mass at a point opposite to the discharge openings whereby the mass is forced outwardly against the side of the tank and against the member having the discharge openings. 75

4. In a dyeing machine, a tank having a bottom and an annular group of discharge openings in the side thereof and below the same an annular imperforate portion, a cover for said tank adapted to be arranged 80 in a manner such that its periphery is adjacent to the discharge openings, said cover having discharge openings near its periphery, and means for delivering the dye liquor to the mass at a point opposite to the discharge. 85

5. In a dyeing machine, a tank having a bottom and an annular row of discharge openings near the upper edge thereof and an annular imperforate portion between such 90 row of openings and the bottom of the tank, a cover for said tank adapted to normally assume a position with its periphery substantially midway between the upper and lower row of perforations, said cover being 95 provided with discharge openings adjacent its periphery, and a distributing means adapted to deliver the dye liquor from the center and from the bottom of said tank whereby the mass is driven toward the side 100 of the tank and against the under side of the cover.

6. In a dyeing machine, a tank having a bottom and a group of discharge openings in the side and extending around the entire 105 tank with an annular imperforate portion between said group of openings and the bottom of the tank, an annular casing on the outside of said tank for receiving the dye liquor from the tank through the discharge 110 openings, a cover for said tank adapted to be arranged with its periphery between the upper and lower row of discharge openings, and a distributing member for directing the dye liquor from the center outward against 115 the side of the tank and upward toward the cover.

7. In a dyeing machine, a tank having a bottom, a cover for said tank, a hollow distributing member comprising a substantially 120 cylindrical portion provided with main supply openings and an upper tapering portion provided with auxiliary supply openings, and a false bottom in the tank.

8. In a dyeing machine, a tank having a 125 bottom, a cover for said tank, a central distributing member having a main substantially cylindrical portion provided with main supply openings, a tapered upper portion provided with auxiliary supply openings, 130

and an annular false bottom extending from the base of said distributing member.

9. In a dyeing machine, a tank, a cover for said tank, a central distributing member 5 engaging the underside of said cover and having a plurality of lugs arranged in horizontal rows, and a false bottom having recesses for receiving said lugs whereby it may be adjusted in different horizontal po-

10 sitions.

10. In a dyeing machine, a tank, a central distributing member having a solid upper boss, a false bottom within the tank, a cover for said tank and comprising an open-ended

cylindrical portion at the center of less bore 15 than the diameter of the solid upper portion of the distributing member, said cover being adapted to rest upon the distributing member at the center, and means engaging the cover for forcing the same down against the 20 top of the distributing member.

In testimony whereof I affix my signature in presence of two witnesses.

JOHN T. PSARSKI.
